RAILWAY CAR WITH HIGH LEVEL SEATS

Ralph W. Haman, Flossmoor, Ill., assignor to Pullman-Standard Car Manufacturing Company, Chicago, Ill., a corporation of Delaware

Application February 27, 1956, Serial No. 567,763

3 Claims. (Cl. 105—345)

This invention relates to railway passenger cars and is primarily concerned with railway passenger cars of the coach type.

An object of the invention is to provide a railway passenger car of conventional height which will serve the same purposes as a dome car. The car is of particular advantage when used by railroads having overhead clearances too low to permit the use of dome cars but offers many advantages useful on railroads generally and affording improved accommodations for the passengers.

Another object of the invention is to provide a railway passenger car of conventional height having a center aisle extending the major portion of the length of the car and floors at opposite sides of the center aisle and above the level of the center aisle floor and extending the major portion of the length of the car and seats mounted on the last named floors and windows in the car walls at the side of and above the seats to give the passengers a better view of the scenery.

Another object of the invention is to provide a railway passenger car of conventional height having a center aisle extending the major portion of the length of the car and floors at opposite sides of the center aisle and above the level of the center aisle floor and extending the major portion of the length of the car and seats mounted on the last named floors and pairs of compartments below the seats and one of each pair of compartments being for luggage and the other of each pair of compartments being for coats and hats or packages.

The foregoing and other objects of the invention will be apparent from the construction and arrangement illustrated in the accompanying drawings wherein

Fig. 1 is a plan sectional view of a portion of a railway passenger coach taken just above the seats;

Fig. 2 is a vertical sectional view taken on the line 2—2 of Fig. 1; and

Fig. 3 is a cross sectional view taken on the line 3—3 of Fig. 1.

In recent years passenger cars of the dome type have been used by the railroads to give passengers a better view of the other cars in the train and of the scenery. However some of these railroads cannot use dome cars because objects along the road such as tunnels were constructed before the use of dome cars was contemplated and there would not be enough overhead clearance for a car of this unusual type. The invention proposes a railway passenger car of conventional height having all of the advantages of a dome car and advantages not present in such cars. The invention comprises a longitudinally extending center aisle and floors on each side of the center aisle floor and below the center aisle floor. Additional floors are provided on each side of the center aisle floor and above the center aisle floor. Seats are arranged one in front of the other along each side wall of the car and are disposed on and secured to the last named floors. Each side wall of the car is provided with windows opposite the seats. Vertical translucent

2

walls are disposed next to the center aisle opposite the seats and are used to give the interior of the car a more striking appearance. Pairs of vertically aligned compartments are located below the seats and one of each pair of compartments is for luggage and the other of each pair of compartments is for coats and hats. Steps are provided so that the passengers may easily reach the seats from the center aisle.

In the drawings, 10 generally designates a railway passenger coach car having an underframe, side walls 11, and a roof 12. The car has end portions 13 and each end portion has a floor 14 at one level. A center aisle 15 extends longitudinally of the car between the end portions 13 and has a floor 16 which is disposed at a level above the floors 14 in the end portions of the car, the floor 16 resting on a pair of supporting members. A floor 17 is disposed between each side wall 11 and the center aisle floor 16 and extends between the end portions 13 of the car and is disposed at the same level as the floors 14 in the end portions of the car. The floors 17 rest on the stringers and on angles secured to the side sills. A floor 18 is disposed between each side wall 11 and the center aisle 15 and extends between the end portions 13 of the car and is disposed at a level higher than the center aisle floor 16. Pairs of reclining seats 19 are arranged one in front of the other along each side wall 11 and are disposed on and secured to the floors 18. A leg rest 20 is mounted on each seat and may be moved to a position under the seat when not in use by the passenger. Each of the side walls 11 is provided with windows 21 opposite the seats and at the eye level of the passenger. Windows 22 are also provided in the area between each side wall and the roof so that the passenger may have a view through the upper portion of the car. A plurality of pairs of spaced partitions 23 are disposed below each pair of seats and each pair of partitions extends between the respective floor 17 and the adjacent floor 18 and also extends from the adjacent side of the center aisle floor 16 to a wall 24 adjacent the respective side wall of the car. A horizontal wall 25 extends between and is secured to each pair of partitions 23 and also extends to and is secured to the wall 24. A back wall 26 extends between and is secured to each pair of partitions 23 and also extends between and is secured to the respective wall 25 and the adjacent floor 18. The respective floor 17 and the respective wall 25 and the respective pair of partitions 23 provide a compartment 27 for luggage. The respective wall 25 and the adjacent floor 18 and the respective pair of partitions 23 with back wall 26 provide a compartment 28 for coats and hats or small packages. A plurality of spaced vertical translucent walls 29 are mounted on each floor 18 and each wall is disposed opposite a pair of seats. The walls 29 give the interior of the car a more striking appearance and also act as modesty shields for the high level seats. Members 30 are secured to the floors 17 and to the floor 16 and a riser 31 containing a grille is secured to the floor 16 and a step 32 is disposed on the riser 31 and a riser 33 partially supports the respective step 32 and is secured to the adjacent floor 18 and a sloping member 34 extends between and is secured to adjacent partitions 23 and is secured to the respective riser 33 and the adjacent floor 18. The riser 33 partially supports the respective floor 18 and the partitions 23 partially support the floor and horizontal members secured to the adjacent side wall partially support the floor and walls 24 and 26 also partially support the floor.

In heating the car air circulates from the center aisle and goes through the grilles in risers 31 under the steps and moves past the heating arrangement adjacent the lower portion of each side wall and then the air moves

up between the respective side wall framing structure and the side wall finish and moves into the car through openings under the window sill of windows 21.

The floors 17 are located approximately six inches below the floor 16 and the floors 18 are located some two feet above the floor 16. The windows in the side walls of the car and the windows between the side walls and the roof give the passengers a much better view of the scenery and surroundings than a conventional railway passenger car with lower level seating similar to the view obtained in a dome car. Applicant's car is of conventional height and serves the same purpose as a dome car and costs less than a dome car. With the higher level seating in applicant's car there are less noises from the train to annoy passengers. The luggage is at the passenger's seat so if he desires to open his luggage while traveling he may do so without any inconvenience. Since the luggage is stored under the seat the passenger does not have to lift it but merely pushes it into the compartment from the center aisle floor. The seats may be reclined and the seats are provided with leg rests and the reclining feature of the seats and the leg rests give the passengers more comfort. Applicant's arrangement may also be used in lounge cars.

From the foregoing it will be seen that applicant has provided a car of conventional height which serves the same purpose as a dome car and can be used by railroads that cannot use dome cars because of low overhead clearances and which provides high level seating throughout the full length of a car having a passageway substantially at normal level and wherein ample facilities are provided for storage of luggage, packages and wraps or the like beneath the floor supporting the seats and between stairways leading to the high level floors and readily accessible from the central passageway.

What is claimed is:

1. In a railway passenger car, a floor extending longitudinally centrally of the car on a single level for the major portion of the length thereof, side walls, a floor disposed between each side wall and the first named floor and extending on a single level the major portion of the length of the car and at a level lower than the first named floor at a distance of some six inches, a floor disposed between each side wall and the first named floor and extending on a single level the major portion of the length of the car and at a level higher than the first named floor at a distance of some two feet, seats arranged one in front of the other along each side wall and disposed on the adjacent one of the third named floors, each of the side walls being provided with windows opposite the seats, a plurality of pairs of spaced partitions disposed below the seats and extending between the respective second named floor and the adjacent one of the third named floors and extending from the adjacent side of the first named floor toward the adjacent side wall, a horizontal wall extending between and secured to each pair of partitions, the space between the respective second named floor and the adjacent wall and the respective pair of partitions providing a place for luggage and the space between the respective wall and the adjacent one of the third named floors and the respective pair of partitions providing a place for coats and hats and both of said spaces being accessible from said first named floor, and a step mounted between adjacent pairs of partitions.

2. In a railway passenger car, a floor extending longitudinally centrally of the car on a single level for the major portion of the length thereof, side walls, a floor

disposed between each side wall and the first named floor and extending on a single level the major portion of the length of the car and at a level lower than the first named floor at a distance of some six inches, a floor disposed between each side wall and the first named floor and extending on a single level the major portion of the length of the car and at a level higher than the first named floor at a distance of some two feet, seats arranged one in front of the other along each side wall and disposed on the adjacent one of the third named floors, each of the side walls being provided with windows opposite the seats, a plurality of pairs of spaced partitions disposed below the seats and extending between the respective second named floor and the adjacent one of the third named floors and extending from the adjacent side of the first named floor toward the adjacent side wall, a horizontal wall extending between and secured to each pair of partitions, the space between the respective second named floor and the adjacent wall and the respective pair of partitions providing a place for luggage and the space between the respective wall and the adjacent one of the third named floors and the respective pair of partitions providing a place for coats and hats and both of said spaces being accessible from said first named floor, a plurality of spaced vertical walls disposed opposite the seats and mounted on the adjacent one of the third named floors, and a step mounted between adjacent pairs of partitions.

3. In a railway passenger car, a floor in each end portion of the car at one level, a floor extending longitudinally centrally of the car between the end portions at a level above the first named floors, side walls, a floor disposed between each side wall and the second named floor and extending on a single level between the end portions of the car and at a level lower than the second named floor at a distance of some six inches, a floor disposed between each side wall and the second named floor and extending continuously on a single level between the end portions of the car and at a level higher than the second named floor at a distance of some two feet, seats arranged one in front of the other along each side wall and disposed on the adjacent one of the fourth named floors, each of the side walls being provided with windows opposite the seats, a plurality of pairs of spaced partitions disposed below the seats and extending between the respective third named floor and the adjacent one of the fourth named floors and extending from the adjacent side of the second named floor toward the adjacent side wall, a horizontal wall extending between and secured to each pair of partitions, the space between the respective third named floor and the adjacent wall and the respective pair of partitions providing a place for luggage and the space between the respective wall and the adjacent one of the fourth named floors and the respective pair of partitions providing a place for coats and hats and both of said spaces being accessible from said second named floor, a plurality of spaced vertical walls disposed opposite the seats and mounted on the adjacent one of the fourth named floors, and a step mounted between adjacent pairs of partitions.
